J. M. GOLDMAN,
AUTOMATIC ELECTROLYTIC CELL,
APPLICATION FILED OCT. 4, 1915.

1,191,300.

Patented July 18, 1916.

INVENTOR

UNITED STATES PATENT OFFICE.

JAY M. GOLDMAN, OF ST. LOUIS, MISSOURI.

AUTOMATIC ELECTROLYTIC CELL.

1,191,300.

Specification of Letters Patent. Patented July 18, 1916.

Application filed October 4, 1915. Serial No. 53,920.

To all whom it may concern:

Be it known that I, JAY M. GOLDMAN, a citizen of the United States, and a resident of the city of St. Louis, in the State of Missouri, have invented certain new and useful Improvements in Automatic Electrolytic Cells, of which the following is a specification containing a full, clear, and exact description, reference being had to the accompanying drawings, forming a part hereof.

My invention relates to improvements in automatic electrolytic cells, wherein the electrodes are so arranged with relation to a flow of liquid to be treated, as to first subject the flow to a maximum of electrolytic action, then subsequently treat the flow to a progressively decreasing electrolytic action, whereby to operate more economically, without a sacrificing of efficiency and wherein the flow of liquid automatically controls the flow of electrical energy.

The object of my invention is to provide an electrolytic cell, so arranged as to relate the electrolytic action on the liquid to be treated to the progression of the liquid through the cell, and so arranged that when the liquid supply is discontinued the current of electricity will also discontinue automatically.

A further and more specific object of my invention is to provide an electrolytic cell, so constructed that liquid entering the cell will receive, initially, a maximum of electrolytic action, and thereafter, as the liquid progresses through the cell, the electrolytic action will progressively decrease, so that at the termination of the course of flow through the cell, the liquid will receive a minimum of electrolytic action; furthermore to provide that in case the flow of liquid to the cell is discontinued, as from time to time, the flow of electrical energy will also automatically discontinue.

With the above objects in view, my improvements consist in certain details of construction and arrangement of parts, herein-after fully set forth, pointed out in my claim and illustrated in the accompanying drawings, in which:

Figure 1 is a vertical longitudinal sectional elevation of a device embodying my invention and is taken on the line 1—1 of Fig. 2. Fig. 2 is a sectional plan taken on the line 2—2 of Fig. 1; and Fig. 3 is a detail of one of the electrical terminals.

Referring to the drawing by numerals, the numeral 4 designates a casing, preferably constructed of glass, which forms the body of the device, which of itself is an open bottomed vessel and rests on a closure 5, which forms a base therefor. By preference this closure or base is metallic and provided centrally with a threaded aperture, to receive a feed pipe 6, whereby water to be treated may be conveyed to the cell formed by the casing body or vessel 4. The pipe 6, by preference is connected with a constant source of supply, not shown, and in order to control the volume of water flowing through the cell I arrange in the pipe 6 a valve 7. The top of the casing, is by preference, formed integrally therewith, apertured to receive a delivery pipe 8. Formed through the bottom of closure 5, of the casing, there is a constantly open drain 9, the function of which will hereinafter be made clear. In this casing or cell there is arranged, two electrodes extending axially thereof, each comprising a number of relatively spaced plates and a support or connecting rod. Secured to the closure 5, on either side of the feed pipe 6 is a socket as shown in Fig. 2, and designated 10 and 11, in each of which is supported a conducting rod, 12, in the socket 10 and 13 in the socket 11.

Arranged in spaced relationship lengthwise of the rod 12 are the electrode plates 14, of one polarity, and on the other rod 13 are the electrode plates 15 of the opposite polarity, and relatively spaced with the plates 14, so as to alternate therewith. Surrounding the rods 12 and 13, except where contact is necessary with the plates 14 and 15 there are the insulating sleeves 16 (on the rod 12) and 17 (on the rod 13).

Between each of the sockets 10 and 11 and the closure, there is arranged an insulating washer 18 and in the openings in the closure there is arranged an insulating bushing 19, through which the threaded stems 20, of the said sockets extend. To each of the stems 20 there is threaded a nut 21, insulated from the closure by a second washer 18, and each threaded stem 20 carries a binding screw 22 whereby to connect conductors, not shown, leading from a source of electric energy, also not shown.

In the construction of my device I preferably mount my electrodes so that all of the parts of both electrodes form a mechani-

cally rigid unit, capable of being introduced into the electric terminal sockets. In order to secure a graded electrolytic action I space the several parts or plates of my electrodes, so that liquid entering between the first set of opposed electrode plates traverses a relatively narrow path while each succeeding interspace thereafter is increased to widen the path of the liquid. In order to further grade the electrolytic action, I alter, relatively, the amount of superficial area of the several plates forming each electrode, so that liquid entering the cell meets plates whose superficial area is nearly that of the section of the cell, leaving just sufficient room at one side for the passage of the liquid. As the liquid passes through the cell it progressively meets succeeding plates, each decreased in superficial area as compared with the former plate until the last plate is reached, which plate is of an area of approximately one-half of the sectional area of the cell.

In the use of my device I erect it substantially vertically in position, connecting the desired form of electrical energy to the terminal sockets 10 and 11 by means of wires secured to the sockets by binding screws 22. I connect a supply of running water to valve 7 by means of which I control the flow of the water. Upon opening valve 7 water is admitted to the cell, covering the bottom closure 5. A portion of this water drains out through the hole 9, which action will hereinafter be considered. The major part of the water rises into the cell and flows out through the delivery pipe 8. The water in rising fills the space beneath the first electrode plate, passes around the plate, which does not occupy the full sectional area of the cell, and then fills the interspace between the first and second electrode plates. As soon as the water reaches the second electrode plate, electric circuit is established and electrolytic action thereby starts. The water continues to rise in the cell, establishing electrical connection with each succeeding plate, which plates are alternately of opposite polarity, and concomitantly therewith establishing electrolytic action throughout the water in the cell. In the first interspace between the electrodes there is relatively a small distance for the electrical energy to travel through the water, and in accordance with Ohm's law the energy transformation is relatively great. This last result is further augmented by the relatively greater amount of superficial area of the electrode plates exposed to the water. In each succeeding interspace both the interspacial distance and the amount of electrode area are modified over the like dimensions in the pre-

ceding interspace, thereby proportionally decreasing the electrolytic action on the water contained in this particular interspace as compared with the electrolytic action already foregone, and as a final result the electrolytic action upon the water passing through the cell is a constantly decreasing one as the water progresses through the cell.

In order to provide for the varying amounts of treatment necessary for waters of varying foreign content the valve 7 is regulated so as to adjust the rate of flow of water to the flow of electrical energy, thereby establishing a suitable relation between the amount of current used to the amount of water treated.

When it is desired to discontinue the treatment of the water, the valve 7 is closed, and water ceases to flow through the cell. At the same time drain 9 which has been open throughout the operation discharges the water which still remains in the cell after the supply is discontinued. As soon as the water level in the cell is lowered to a point where it no longer makes connection with parts of the circuit of opposite polarity, there is no longer the existence of an electric circuit and the flow of electrical energy is thereby automatically discontinued.

Considering my electrolytic cell from a bactericidal or sterilizing standpoint as well as from a chemical eliminative standpoint, it will be understood, by persons versed in the art, that by the relative spacing arrangement of, and the variable superficial areas of the electrode plates or elements, I am enabled to obtain the desired or necessary electrolytic action with a relatively small energy consumption. In the elimination of bacteria and dissolved foreign substances, the element of time is essential. The initial requirement is for a sufficient amount of electrolytic action to greatly enervate bacteria and to initially break down chemical structures of the foreign dissolved substances. When once either or both of these effects has been produced and the so-called inertia has been broken down, the continuation of the process may be accomplished with a relatively lower rate of electrolytic action, the requirement for electrolytic energy being substantially inverse to the amount of removable substance remaining in the water.

I claim:—

A structure comprising electrode elements of opposite polarity in alternate arrangement, of increasing relative spacing and of decreasing relative superficial areas, lengthwise of the electrode.

In testimony whereof, I have signed my name to this specification.

JAY M. GOLDMAN.
